UNITED STATES PATENT OFFICE

2,575,501

QUICK DISASSEMBLY SLIDE FASTENER

Frederick Ulrich, Jersey City, N. J., assignor to
 Conmar Products Corporation, Newark, N. J., a
 corporation of New Jersey

Application January 27, 1949, Serial No. 73,097

7 Claims. (Cl. 24—205.11)

1

The present invention relates to improvements in slide fasteners, and more particularly to slide fasteners of the quick disassembly type.

In quick disassembly slide fasteners a releasing end stop or so-called "slip stop" is provided for stopping the slider when drawn with a normal closing force. However, a strong pull draws the slider past this temporary or releasing end stop whereupon the stringers are free to be separated by a quick stripping action without moving the slider back to the bottom stop. To accomplish this quick stripping action the slider must be released by one stringer, usually termed the slider-releasing stringer, and maintained on the other stringer, usually termed the slider-retaining stringer, so that the slider, after quick stripping, may be returned to the bottom stop for reassembly of the two stringers.

Prior to my invention it was necessary to remove the cords beyond the uppermost fastener element on the slider-releasing stringer. The stringer would not release the slider because the slider's flanges or rails would engage the cords upon the tape edge and prevent the stringer from passing out from between the wings of the slider. This required the use of beaded tape formed by cord sewing, because a tape having its beaded edge formed by weaving or folding could not have its tape edge thickness reduced without mutilating the tape beyond use. Sections of sewn cords had to be removed by a cutting operation with the result that the cut cord edges would quickly fray and give the fastener an unsightly appearance. Attempts have been made to protect the cut cord edges against fraying by some auxiliary means, one such means being bar-tacks. However, besides adding to the cost of the product, these attempts have not been very successful. To initially cut the cords is one extra operation, and to add the auxiliary means is another, thus adding to the cost of manufacturing the finished fastener. Other structures have been proposed, requiring complex special slider and the addition of mechanical elements to the tape, but these have not proved commercially successful.

By means of my invention it now is practical to fabricate a quick disassembly fastener which eliminates the necessity for cutting off the cords with its attendant disadvantages of an inferior product which costs more to produce, yet which employs a simple slider having a tape slot of uniform width, and a tape extension which is devoid of mechanical additions. Furthermore, the invention permits the use of tapes having beaded edges formed by weaving or folding, which hitherto could not be used for quick disassembly fasteners.

To accomplish the foregoing general objects, and other more specific objects which will hereinafter appear, my invention resides in the novel quick disassembly slide fastener elements and

2

their relation one to another as is hereinafter more particularly described in the following specification. The specification is accompanied by drawings, in which:

5 Fig. 1 is a plan view of a quick disassembly type of slide fastener embodying some of the principles of the present invention;

10 Fig. 2 shows the upper end of the slide fastener with the slider moved beyond the releasing end stop and prior to stripping the stringers of the fastener apart, the slider pull and lug being omitted for the purpose of clarity in illustration;

15 Fig. 3 is a view similar to Fig. 2 showing the fastener as the stringers are being stripped apart;

15 Fig. 4 is a view similar to Figs. 2 and 3 illustrating the fastener after the stringers have been disengaged, with the slider released by one stringer and retained on the other;

Fig. 5 is a perspective view of one form of slider 20 which permits the stringers of a quick disassembly fastener to be stripped apart, notwithstanding the presence of a beaded tape edge above the uppermost fastener element on the slider-releasing stringer;

25 Fig. 6 is a section taken approximately in the plane of line 6—6 of Fig. 2;

Fig. 7 is a section taken approximately in the plane of line 7—7 of Fig. 3;

30 Fig. 8 is a view similar to Fig. 1 wherein the releasing end stop is secured to the slider-releasing stringer instead of the slider-retaining stringer;

Fig. 9 is a section similar to Fig. 6 illustrating a modified form of slider for use with the fastener 35 shown in Fig. 8;

Fig. 10 is a section similar to Fig. 7 illustrating the manner in which the slider shown in Fig. 9 releases the beaded tape edge in the stripping operation;

40 Fig. 11 is a fragmentary, plan view similar to Fig. 8 illustrating a quick disassembly slide fastener having another form of releasing end stop;

Fig. 12 is a view similar to Figs. 6 and 9 illustrating another form of slider which may be used in the present invention; and

45 Fig. 13 is a view similar to Figs. 6, 9 and 12 illustrating still another form of a slider which may be used in the present invention.

Referring to the drawings, particularly Figs. 1 50 through 7, the slide fastener comprises a slider-retaining stringer 12 and a slider-releasing stringer 14, each provided with spaced, interlockable fastener elements 16, and a slider 18 movable therealong by means of a suitable handle or so-called "pull" 20. The stringers 12 and 14 comprise tapes 22 having beaded edges 24 about which the fastener elements 16 are clamped or secured. As illustrated in Figs. 6 and 7, the beaded edges 24 are formed by sewing cords 26 upon opposite edges of the tape 22.

60 A releasing end stop or so-called "slip stop" 28

is located near the closed end of the slide fastener. One stringer, in this case stringer 12, has the releasing end stop 28 secured thereto intermediate adjacent fastener elements 16. The stringer 12 also is provided with a true or permanent top stop 30. When the slider is forcibly pulled past the stop 28, as shown in Fig. 2, it is finally halted by the top stop 30. To permit the stringers to be separated, the top stop 30 is placed upwardly from the endmost fastener element on the other stringer 14, designated 16', by an amount slightly greater than the length of the slider 18. To positively insure retention of the slider 18 on the stringer 12, even when using a symmetrical slider described later, the fastener elements which will engage fastener element 16' and the positive stop 30, as indicated by elements 17.

The slide fastener illustrated is of the fully separable type having the usual separable bottom stop construction, the one shown in Fig. 1 being disclosed in U. S. Letters Patent 2,216,794 to Frederick Ulrich, granted October 8, 1940. The terms "top" and "bottom" are here used as is customary in the art for the fastener may, of course, be used in any position. The separable bottom stop includes a stud 32 clamped onto the beaded edge 24 of the stringer 12. A clip 34 clamped onto the lower portion of the stud 32 provides a socket for removably receiving a pin 36 which is clamped onto the beaded edge of the stringer 14. As is well known in the art, when the slider 18 is in its lowermost position on the slide fastener and in contact with the top of the clip 34, the pin 36 may be threaded through the slider 18 and into or out of the socket.

In general, the separable bottom stop may be of any desired construction. Instead of the pin and clip type of fully separable end stop assembly, a fully separable end stop assembly may be used of the type disclosed in the pending application of Albert Bashover, Serial Number 59,330, filed November 10, 1948, now Patent No. 2,553,230, patented June 26, 1951, having the same assignee as the present application. If this type of separable end stop assembly is selected, fastener elements of the double-acting type are used in lieu of the one-way type of fastener element 16 illustrated.

The releasing end stop or "slip stop" 28 is of the type disclosed in the pending application of Otto J. Moehler, Serial Number 29,837, filed May 28, 1948, having the same assignee as the present application. For the purpose of this invention, it is sufficient to state that this type of releasing end stop co-acts with a fastener element on the opposing stringer within the slider to cause the slider to be halted when a normal pull is exerted. However, when subjected to a stronger pull, the slider moves past the stop 28 and slides upwardly until stopped by the top stop 30.

In accordance with my invention, and unlike previous quick disassembly slide fastener constructions, the cords 26 on the slider-releasing stringer 14 are not removed or cut off above the uppermost fastener element 16'. On the one hand there is no need to remove the cords, and on the other hand there is no need to add mechanical or metal parts to the tape. This highly desirable aspect of the fastener is made possible by the construction of the slider. The slider is formed with a tape slot on the side of the slider-releasing stringer, which slot is sufficiently large to allow the beaded or uncut cord edge of the tape to pass therethrough. Though the tape

slot is enlarged, the slider is formed so that it nevertheless will prevent interlocked fastener elements from unmeshing when the fastener is subjected to cross-pull below the slider. While the slider is not a standard slider, it is nevertheless a very simple slider which can be made as readily and as cheaply as a standard slider, for the tape slot is a simple slot which is straight and uniform in width throughout its length, just like that of an ordinary slider.

As shown in Figs. 5, 6 and 7, the slider 18 comprises a top wing 38 and a bottom wing 40 connected together by a neck or post 42. The top wing 38 is provided with the usual pair of in-turned rails or flanges 44, 46. The top wing also has the usual lug 48 to which the pull 20 is secured. However, the bottom wing 40, instead of being provided with the usual pair of in-turned rails or flanges, is formed with but one rail 50 on the left or the slider-retaining stringer side. By forming the slider 18 without a rail or flange on the slider-releasing stringer side, the resulting tape slot, designated T, provides an opening of sufficient size to permit the beaded edge of the tape above the uppermost fastener element 16' on the slider-releasing stringer to come out without difficulty. This beaded edge portion of the tape is designated 24'. The slider wings 38, 40, the neck 42 and the rails 44, 46 alone provide the requisite Y-shaped channel which serves to cam the fastener elements 16 into or out of engagement with each other. Though the tape slot has been opened, the dimensions of the fastener elements 16 with respect to the slider channel are such that the meshed fastener elements will not unmesh when cross-pull is applied to the fastener below the slider. Figs. 3 and 7 illustrate how the beaded edge portion 24', devoid of fastener elements thereon, passes laterally through the tape slot T when a transverse pull is exerted upon the stringers 12 and 14, the slider 18 being beyond the releasing end stop 28. Fig. 4 shows how the slider-releasing stringer 14 is completely disengaged from the slider 18 and retained by the permanent stop 30 upon the stringer 12.

While the tape slot T is made larger than in the ordinary slider, it is preferred that it be made somewhat smaller than the thickness of the beaded tape edge 24'. For example, it is considered good manufacturing practice to fabricate an ordinary slider, one having four rails, for a so-called "#5" separable fastener with the following dimensions:

	Inches
Rail height	0.033 to 0.034
Body opening	0.102 to 0.1065
Tape slot	0.035 to 0.040

Rail height, body opening and tape slot are designated "a," "b" and "c," respectively, in Figs. 5, 6 and 7. The beaded edge thickness formed by sewing cords on opposite sides of the tape measures from 0.087 to 0.090 inch. The beaded edge simply will not come out of a tape slot, "c" of from 0.035 to 0.040 inch. It, therefore, was necessary heretofore to cut off the cords to permit stripping the stringers apart. However, by forming the slider without one rail, the tape slot is opened by an additional 0.033 to 0.034 inch, thereby resulting in a tape slot T having an opening of from 0.068 to 0.073 inch. Instead of a difference between beaded edge thickness and tape slot on the order of 0.048 to 0.053 inch with a slider having the usual pair of tape slots of width "c," the difference with the present slot T is on the order of only 0.015 to 0.020 inch. While the tape slot

T is not quite as large as the thickness of the beaded tape edge, it has been found that the beaded edge nevertheless will pass therethrough. Presumably the textile materials possess sufficient resiliency or compressibility to enable the beaded edge to come through the enlarged slot without undue resistance. Moreover, in applying a transverse pull to the stringers to strip them apart, as shown in Figs. 3 and 7, the beaded edge 24' rarely, if ever, moves toward the slot in a perfectly upright position; that is to say, there usually is some angular displacement imparted to the beaded edge, as shown for example in Fig. 7, which lessens the effective height of the beaded edge presented to the slot. Furthermore, if in stripping the stringers apart, the cord adjacent the rail 44 strikes said rail, the beaded edge will pivot about this point of contact and tilt, as also is shown in Fig. 7, thereby permitting the tape easily to be pulled from within the slider.

It shall be understood that the numerical dimensions for a "#5" fastener are given by way of specific example only. Reasonable variations may be made depending upon inherent differences in slider structure and manufacture without departing from the spirit of the disclosed invention. Moreover, the dimensions are of interest from the standpoint of the relation of one to another rather than to their actual values, especially the relation of the tape bead to the widened slot T. Thus, it would be obvious how to dimension sliders for different fastener sizes.

By enlarging the tape slot without shortening the height of the adjoining rail 44, said rail 44 in combination with the rail 46 alone affords a Y-shaped channel which prevents interlocked fastener elements 16 from unmeshing when cross-pull is applied to the stringers below the slider. I have found that even the rail 50 is unnecessary insofar as it supplies resistance to cross-pull disengaging forces applied to meshed fastener elements. The rail 50 is provided primarily because the particular releasing end stop 28 illustrated requires the presence of rails behind it when co-acting with an opposing fastener element. If instead, a releasing end stop for example of the type disclosed in the Griffin patent, 2,422,093, issued June 10, 1947, were to be used, the rail 50 also may be omitted. This type of releasing end stop comprises a resilient member which exerts pressure upon the opposite inner flat surfaces of the wings, the slider rails playing no part in the halting action. With rail 50 omitted the slider would be symmetrical.

Fig. 8 shows a quick disassembly slide fastener in which the releasing end stop 28 shown in Fig. 1 is attached to the slider-releasing stringer 14 instead of the slider-retaining stringer 12. The change in location of the releasing end stop, now designated 28', requires slight modification of the slider 18. The modified slider is designated 52, and since all other components of the fastener are the same, the same reference numerals are used for these components.

As hereinbefore stated, the illustrated type of releasing end stop requires the presence of two slider rails or portions thereof on the side of the fastener upon which the releasing end stop is located. As shown in Fig. 9, the slider 52 comprises a top wing 54 and a bottom wing 56 connected by the usual neck or post. The top wing 54 possesses the usual pair of inturned rails 58, 60 and the bottom wing 56 is provided with the usual rail 62. However, instead of the ordinary equal height fourth rail, indicated by the dotted

outline "x," a low rail 64 is formed on the releasing-stringer side of the slider. The height "d" of the rail 64 is approximately 0.010 inch. This very small rail height is sufficient to permit the releasing end stop 28' to function properly, and yet provide a wide tape slot between the rails 58 and 64, designated T', which will allow the beaded edge 24' to pass laterally therethrough. Fig. 10 illustrates the manner in which the beaded edge 24' passes out through the tape slot T' during the stripping action. The passage of the beaded tape edge through the slot takes place in essentially the same way as described with respect to the fastener shown in Figs. 1 to 7. The beaded edge is subjected to slightly greater wear, however, because of the presence of the partial rail 64, and for that reason a fastener which permits the use of the slider 18 is preferred.

Here again the slider may, if desired, be made symmetrical by reducing the height of the rail 62 to equal that of the rail 64. Such symmetry would not affect the functioning of the present invention, which depends directly on the slot width at the stringer releasing side of the slider. The other side is of no concern except insofar as it may affect the operation of some kinds of "slip stop."

Fig. 11 illustrates a fastener identical with the fastener shown in Fig. 1 but utilizing another type of releasing end stop, shown at 66. The releasing end stop 66 is of the type disclosed in the pending patent application of Claude Disinger, Serial Number 36,726, filed July 2, 1948, now patent No. 2,558,239, patented June 26, 1951, having the same assignee as the present application. This releasing end stop also co-acts with a fastener element on the opposing stringer. The construction and principle of operation of the releasing end stop 66, however, is such that it does not require the presence of slider rail surfaces, or even portions thereof, on its side of the slider. The engagement of an opposing fastener element with the releasing end stop 66 causes the beaded edge upon which the releasing end stop is mounted to be flexed to provide resilient resistance to the passage of the slider, and hence it may be attached to either the stringer 14 or the stringer 12, as shown. This permits the use of the slider 18 with its larger tape slot regardless of the location of the stop 66. The right hand rail may be omitted, as in Fig. 6, or both right and left hand rails omitted for symmetry, and the slip stop 66 may be placed on either side in either case.

Fig. 12 illustrates a modification of the slider 18 shown in Figs. 1 to 7. Instead of the tape slot being enlarged by omitting one rail on the bottom wing, this time the top wing is formed with only one rail, the bottom wing having the usual pair of rails. Here too the slider may be made symmetrical by omitting both top rails.

Fig. 13 illustrates a variation of the slider 52 shown in Figs. 9 and 10. Instead of the tape slot T' being enlarged by forming a low rail 64 on the bottom wing, the low rail 74 is formed on the top wing, with rails of usual height formed on the lower wing.

For the reasons heretofore stated which permit the omission of the rail 50 in slider 18, the top wing of the slider shown in Fig. 13 may be provided with a pair of low rails instead of one low rail as shown. Such a modification affords symmetry of the slider wings. In all cases one slider wing preferably has rails of full height. In other words, the tape slot is widened by changing only

one of the two rails at that slot, the other rail being left at full height to best hold the fastener elements.

The sliders depicted in the drawings are of the non-locking type. However, it is within the scope of the invention to use a locking type of slider, such as those commonly referred to in the art as automatic lock, pin lock, cam lock, and wing lock sliders.

While the invention has been specifically described with relation to beaded edge tapes formed by sewing cords on opposite sides thereof, it is within the scope of the invention to utilize tapes having their beaded edges formed by weaving a cord or cords as an integral part or parts of the tape. Random examples of such tapes are described in the Jones Patents 2,333,314 and 2,373,835, issued November 2, 1943 and April 17, 1945, respectively. The invention also permits the use of tapes having their beaded edges formed by folding, a random example of this type of tape being described in the patent to Kiessling, 1,900,564, issued March 7, 1933. Prior to the present invention, such tapes could not be used for a quick disassembly fastener because it was impossible to reduce the thickness of the beaded edge without ruining the tape.

The slider constructions described afford an additional advantage in a fully separable fastener of the pin and clip type such as shown in Fig. 1, because the enlarged tape slot facilitates threading the pin through the slider and into and out of the socket provided by the clip.

While a quick disassembly fastener of the fully separable type has been described, the invention is utilizable with a quick disassembly fastener having a bottom stop which is not fully separable, such as disclosed in the co-pending application of David Rabinow and Otto J. Moehler, Serial Number 613,890, filed August 31, 1945, having the same assignee as the present application.

It is believed that the construction and operation of my improved quick-disassembly fastener, as well as the advantages thereof, will be apparent from the foregoing detailed description. The main general advantages are obvious, for the cost of manufacture is substantially reduced, yet at the same time a superior product is obtained. Other advantages are that the slider, while not a standard slider, is one which is as simple, and in a sense even simpler, than a standard slider, and may be made at equally low cost, and without changing the conventional methods of fabrication. Another is that the slider releasing stringer is made at minimum cost, for the only requirement is the omission of some of the fastener elements. There is no need to remove the cords, and at the same time there is no need to add any metal or mechanical parts to the tape. The fastener, and the garments in which the fastener is used, are improved in appearance by the retention of the cords, and by the omission of conspicuous or unsightly metal parts. Another advantage is the freedom of choice of tape, for the present invention may be employed with a woven or folded tape, as well as with a tape having sewn cords. Still another advantage is that it is easier to thread the pin of a fully separable bottom stop thru the slider.

It will be apparent that while I have shown and described my invention in several preferred forms, changes may be made in the constructions disclosed, without departing from the spirit of the invention as sought to be defined in the following claims. In the claims the expression "rail of

reduced height" is intended to include the extreme case of reduction all the way down to zero height.

I claim:

5 1. A quick disassembly slide fastener comprising a slider-retaining stringer, a slider-releasing stringer, a releasing end stop secured to the fastener near the top thereof, and a slider having a Y-shaped channel, said stringers being formed of beaded edge tape having spaced, interlockable fastener elements secured thereto, said slider-releasing stringer having the beaded edge extending beyond its uppermost fastener element for the length of the tape, said slider being formed with a tape slot of uniform width dimensioned to permit the slider, when beyond the releasing end stop and said uppermost fastener element, to be released readily by the slider-releasing stringer notwithstanding the presence of the beaded edge, said slider comprising spaced top and bottom wings joined by a neck at one end thereof, only one of said wings being provided with a pair of inturned rails, the other of said wings having a rail on the slider-retaining stringer side of the fastener only, whereby the tape slot on the slider-releasing stringer side is wider than the tape slot on the slider-retaining stringer side and is wide enough to pass the beaded edge of the tape.

30 2. A quick disassembly fully separable slide fastener comprising a pair of stringers each formed of beaded edge tape having spaced, interlockable fastener elements secured thereto, a slider having a Y-shaped channel, a fully separable bottom stop assembly, a positive top stop secured to one of the stringers and spaced above the endmost fastener element on the second stringer by an amount greater than the length of the slider, said second stringer having the beaded edge extending beyond its endmost fastener element for the length of the tape, said beaded edge beyond said endmost fastener element being the regular simple flexible beaded edge of the tape, and a releasing end stop secured to one of said stringers intermediate at least a pair of adjacent fastener elements, said slider being formed with a tape slot of uniform width dimensioned to permit the slider, when beyond the releasing end stop and the endmost fastener element on the second stringer, to be released readily by the second stringer notwithstanding the presence of the beaded edge, said tape slot facilitating assembly of the stringers at the bottom stop, said slider comprising spaced top and bottom wings joined by a neck at one end thereof, only one of said wings being provided with a pair of inturned rails, the other of said wings having a rail on the slider-retaining stringer side of the fastener only, whereby the tape slot on the slider-releasing stringer side is wider than the tape slot on the slider-retaining stringer side and is wide enough to pass the beaded edge of the tape.

45 3. A quick disassembly slide fastener comprising a slider-retaining stringer, a slider-releasing stringer, a releasing end stop secured to the fastener near the top thereof, and a slider having a Y-shaped channel, said stringers being formed of beaded edge tape having spaced, interlockable fastener elements secured thereto, said slider-releasing stringer having the beaded edge extending beyond its uppermost fastener element for the length of the tape, said slider being formed with a narrow tape slot on the slider retaining side, said slot being of uniform width and

being too narrow to escape from the beaded edge of the tape, and said slider being formed with a wider tape slot of uniform width on the slider releasing side, said wider tape slot being dimensioned to permit the slider, when beyond the releasing end stop and said uppermost fastener element, to be released readily by the slider-releasing stringer notwithstanding the presence of the beaded edge.

4. A quick disassembly slide fastener comprising a slider-retaining stringer, a slider-releasing stringer, a releasing end stop secured to the fastener near the top thereof, and a slider having a Y-shaped channel, said stringers being formed of beaded edge tape having spaced, interlockable fastener elements secured thereto, said slider-releasing stringer having the beaded edge extending beyond its uppermost fastener element for the length of the tape, said slider being formed with a tape slot of uniform width dimensioned to permit the slider, when beyond the releasing end stop and said uppermost fastener element, to be released readily by the slider-releasing stringer notwithstanding the presence of the beaded edge, said slider comprising spaced top and bottom wings joined by a neck at one end thereof, only one of said wings being provided with a pair of inturned rails of standard height, the other of said wings being provided on the slider-retaining stringer side with an inturned rail of standard height and on the slider-releasing stringer side of the fastener with an inturned rail having a height substantially less than the standard height, whereby the tape slot on the slider-releasing stringer side is wider than the tape slot on the slider-retaining stringer side and is wide enough to pass the beaded edge of the tape.

5. A quick disassembly fully separable slide fastener comprising a pair of stringers each formed of beaded edge tape having spaced, interlockable fastener elements secured thereto, a slider having a Y-shaped channel, a fully separable bottom stop assembly, a positive top stop secured to one of the stringers and spaced above the endmost fastener element on the second stringer by an amount greater than the length of the slider, said second stringer having the beaded edge extending beyond its endmost fastener element for the length of the tape, said beaded edge beyond said endmost fastener being the regular simple flexible beaded edge of the tape, and a releasing end stop secured to one of said stringers intermediate at least a pair of adjacent fastener elements, said slider being formed with a narrow tape slot on the slider retaining side, said slot being of uniform width and being too narrow to escape from the beaded edge of the tape, and said slider being formed with a wide tape slot of uniform width on the slider releasing side, said wide tape slot being dimensioned to permit the slider, when beyond the releasing end stop and the endmost fastener element on the second stringer, to be released readily by the second stringer notwithstanding the presence of the beaded edge, said wide tape slot facilitating assembly of the stringers at the bottom stop.

6. A quick disassembly fully separable slide fastener comprising a pair of stringers each formed of beaded edge tape having spaced, interlockable fastener elements secured thereto, a slider having a Y-shaped channel, a fully separable bottom stop assembly, a positive top stop secured to one of the stringers and spaced above the endmost fastener element on the second

stringer by an amount greater than the length of the slider, said second stringer having the beaded edge extending beyond its endmost fastener element for the length of the tape, said beaded edge beyond said endmost fastener element being the regular simple flexible beaded edge of the tape, and a releasing end stop secured to one of said stringers intermediate at least a pair of adjacent fastener elements, said slider being formed with a tape slot of uniform width dimensioned to permit the slider, when beyond the releasing end stop and the endmost fastener element on the second stringer, to be released readily by the second stringer notwithstanding the presence of the beaded edge, said tape slot facilitating assembly of the stringers at the bottom stop, said slider comprising spaced top and bottom wings joined by a neck at one end thereof, only one of said wings being provided with a pair of inturned rails of standard height, the other of said wings being provided on the slider-retaining stringer side with an inturned rail of standard height and on the slider-releasing stringer side of the fastener with an inturned rail having a height substantially less than the standard height, whereby the tape slot on the slider-releasing stringer side is wider than the tape slot on the slider-retaining stringer side and is wide enough to pass the beaded edge of the tape.

7. A quick disassembly fully separable slide fastener comprising a pair of stringers each formed of beaded edge tape having spaced, interlockable fastener elements secured thereto, a slider having a Y-shaped channel, a fully separable bottom stop assembly, a positive top stop secured to one of the stringers and spaced above the endmost fastener element on the second stringer by an amount greater than the length of the slider, said second stringer having the beaded edge extending beyond its endmost element for the length of the tape, said beaded edge beyond said endmost element being the regular simple flexible beaded edge of the tape, and a releasing end stop secured to one of said stringers intermediate at least a pair of adjacent fastener elements, said slider comprising spaced top and bottom wings joined by a neck at one end thereof, one only of said wings being provided with a pair of inturned rails, the other of said wings having a rail on the slider-retaining stringer side of the fastener only, the resulting wide tape slot being wider than that on the slider-retaining side and being dimensioned to pass the beaded edge of the tape and thereby to permit the slider when beyond the releasing end stop and the endmost element on the second stringer to be released readily by the second stringer notwithstanding the presence of the beaded edge, and said wide tape slot also facilitating assembly of the stringers at the bottom stop.

FREDERICK ULRICH.
